A. F. KRAUSE

BOILER TUBE CLEANER

Filed March 18, 1921

Inventor,
Albert J. Krause,
by Geiger & Dohr,
Attorneys.

UNITED STATES PATENT OFFICE.

ALBERT F. KRAUSE, OF BUFFALO, NEW YORK, ASSIGNOR TO GENERAL SPECIALTY COMPANY OF BUFFALO, NEW YORK, A COPARTNERSHIP.

BOILER-TUBE CLEANER.

Application filed March 18, 1921. Serial No. 453,811.

To all whom it may concern:

Be it known that I, ALBERT F. KRAUSE, a citizen of the United States, residing at Buffalo, in the county of Erie and State of New York, have invented new and useful Improvements in Boiler-Tube Cleaners, of which the following is a specification.

This invention relates to the rotary cleaners which are employed for removing scale 10 from the tubes of water-tube boilers, and more particularly to the type comprising a rotary head and arms or members loosely connected to the head and carrying toothed cutters which are thrown out against the 15 scale by centrifugal force.

The effectiveness of this class of cleaners depends on the speed of rotation of the cutter head, the blow delivered by the toothed cutters being more powerful the greater the 20 velocity of the head.

The arrangement of the cutter-carrying members has hitherto been such as to counteract the driving force of the cutter head to a considerable extent, thus retarding its 25 speed and reducing the efficiency of the tool.

It is the object of my invention to improve the construction of this type of cleaners with a view of reducing such retarding or counteractive force to a minimum and 30 increasing the effectiveness of the tool.

In the accompanying drawings: Figure 1 is a side elevation of the tool. Figures 2 and 3 are transverse sections on the correspondingly numbered lines in Fig. 1. Figure 4 is a longitudinal section on line 4-4, Fig. 3. Figures 5 and 6 are perspective views of the link-members which connect the cutter-carrying arms with the rotary head. Figure 7 is a fragmentary sectional 40 elevation of one of the tie bolts and the adjacent frame-member of the head. Figure 8 is a cross section of said bolt.

Similar characters of reference indicate corresponding parts throughout the several 45 views.

The head or frame of the cleaner may be of any suitable construction, that shown in the drawings comprising front and rear plates 1, 2 and a pair of longitudinal tie bolts 3 rigidly connecting the same and arranged on opposite sides of the axis of the head. On its rear side the inner plate is provided with a screw socket 4 adapted to receive the front end of a shaft 5 which is 55 driven by a motor, not shown in the draw-

ings. A turbine motor is preferred for this purpose, but any other suitable type may be employed.

In the construction shown in the drawings, two cutters or sets of cutters 6 are arranged on diametrically opposite sides of the head, but a different number may be employed, if desired. These cutters have the usual longitudinal teeth 6^a and are composed of a number of sections arranged side by side, as shown. The sections of each cutter are mounted to rotate on a shaft or spindle 7 arranged lengthwise of the head and secured in the front ends of a pair of parallel bars or carrying-arms 8 arranged to swing crosswise of the head. These carrying arms or members are loosely linked to the head in such manner that the cutters are caused to yield or rebound from projections of the scale in a substantially straight line located between two lines, one drawn radially through the axes of the cutter and the head and the other through the cutter tangentially to the circle of rotation of the axis of the cutter about the axis of said head.

As the linked connections of the two sets of carrying arms are alike, a description of one set will apply to both. The arms of each set are pivoted upon a longitudinal rod 9 journaled in openings 9^a in the outer ends of a pair of parallel links 10 which are in turn pivoted upon the adjacent tie bolt 3. These links are rigidly tied together by a longitudinal web or bar 11 which is concaved or grooved on its inner side, as shown at 12, to receive the adjacent sides of the rod 9 and tie bolt 3. Located between the cutter shaft 7 and the rod 9 is a similar pair of links 13 provided at their inner ends with trunnions 14 journaled in the front and rear plates 1 and 2, and rigidly united by a longitudinal bar or web 15. At their outer ends the links 13 are pivoted to the corresponding carrying arms 8 by studs or pins 16. These pins are provided with shoulders 17 which bear against the outer sides of the carrying arms, while the outer ends of the pins are overlapped by the plates 1 and 2, whereby the pins are reliably held against displacement.

As shown in Figs. 4 and 6, the webs 11 are provided next to the links 10 with recesses 11^a to receive the inner ends of the arms 8.

It will be understood from the foregoing

that the movement of these arms is similar to that of a parallel ruler, the cutters moving substantially in the line above described when thrown out by centrifugal force against the scale and also in rebounding or re-acting from the scale.

By pivoting or linking the cutter-shafts to the head, as described and shown, the cutters yield in the direction of the reactive force exerted on them by the scale-projections, with the result that they offer practically no opposition to their driving force, thereby permitting the cutter head to rotate at a higher speed and correspondingly increasing the effectiveness of the tool.

The line A in Fig. 2 indicates the direction in which the driving force is exerted on the rotary cutter-head; the line B the direction in which the cutters yield or rebound from scale-projections, and the line C the direction of the force of the blow exerted on the cutters by such projections. It will be noted that the line B is coincident with the line C. The dotted line D indicates the circle of rotation of the cutter axes. The line A is also the line hereinbefore referred to as being tangential to that circle.

In rotary cleaners of this type, as hitherto constructed, the cutters are incapable of yielding in the direction of the reactive force applied to them by scale projections, but do so in a line at a considerable angle to that direction, the result being that a large portion of said force counteracts the rotative or driving force of the cutter head, materially retarding its speed and impairing the efficiency of the tool.

This improved construction also lessens friction and wear of the parts and avoids twisting strains, rendering the tool more durable. At the same time, the cost of the tool is not increased.

The connections between the cutter shafts and the head may obviously be modified within the scope of the appended claims, and I do not therefore wish to be limited to the particular link-connections illustrated in the drawings.

Upon removing the nuts at the front ends of the tie bolts 3, the other parts of the head, including the cutters, can be slipped off said bolts without disturbing them, thus permitting the cutters to be readily renewed.

In order to allow all of said parts including the tie bolts to be removed from the rear plate 2, without otherwise dismembering the head, the tie bolts are preferably made readily detachable from said plate. For this purpose, these bolts pass through openings in said plate and their projecting rear ends are provided in one side with a transverse notch 18, with which a split ring 19, preferably of the key-ring type, is adapted to interlock, as shown in Figs. 1, 7 and 8.

Upon disengaging the ring from the bolts,

they together with the rest of the cutter-head can be removed from the rear plate 2, without disassembling other parts. This feature facilitates renewal of that plate in case it should be broken.

70 I claim as my invention:

1. A boiler tube cleaner, comprising a rotatable head, a cutter, a member carrying the cutter and movably mounted on said head, said carrying member extending across 75 and on opposite sides of the head, and controlling means for causing said carrying member to move in the direction of its length on the rebound of the cutter.

2. A boiler tube cleaner, comprising a rotatable head, a cutter, a member carrying the cutter and movably mounted on said head, said carrying member extending across said head, and controlling means for causing said carrying member to move in 85 the direction of its length on the rebound of the cutter.

3. A boiler tube cleaner, comprising a rotatable head, a cutter, a member carrying the cutter and extending across said head 90 and movable relatively thereto, and a connection between said carrying member and the head for confining the carrying member to movement in the direction of its length and in a substantially straight line located 95 between two lines, one drawn radially through the axes of the cutter and the head and the other through the cutter-axis tangentially to the orbit in which the cutter revolves about the axis of the cutter.

100 4. A boiler tube cleaner, comprising a rotatable head, a cutter, a member carrying the cutter and extending transversely of said head, and parallel links movable transversely of said head and pivoted at their outer ends to said carrying member and at their inner ends to said head, the axis of the cutter being parallel with the axis of said head.

110 5. A boiler tube cleaner, comprising a rotatable head, a cutter, an arm carrying the cutter and arranged transversely of the head, parallel links movable crosswise of the head, and pivot-members connecting opposite ends of said links with said carrying 115 arm and said head, respectively, and arranged substantially parallel with the axis of the head.

120 6. The combination of a rotatable head comprising front and rear plates and a longitudinal tie bolt connecting said plates, front and rear links mounted on said bolt to swing crosswise of said head, a second pair of links pivoted to said plates and arranged parallel with the first-named links, 125 front and rear arms pivoted to the free ends of the corresponding pairs of links, and cutters carried by said arms.

130 7. The combination of a rotatable head, comprising front and rear plates, a tie-mem-

ber connecting said plates, a pair of links mounted on said tie member to swing crosswise of said head, a web connecting said links, a second pair of links pivoted to said plates and arranged parallel with the first-named links, front and rear arms pivoted to the free ends of the corresponding pairs of links, and cutters carried by said arms.

8. The combination of a rotatable head, comprising front and rear plates, a tie-member connecting said plates, a pair of links mounted on said tie member to swing crosswise of said head, a second pair of links pivoted to said plates and arranged parallel with the first-named links, a longitudinal

web connecting the last-named links, front and rear arms pivoted to the free ends of the corresponding pairs of links, and cutters carried by said arms.

9. The combination of a rotatable head including front and rear plates, a cutter-shaft, arms carrying opposite ends of said shaft, links pivotally mounted on said plates to swing crosswise of said head, and pivot-pins connecting said arms with the free ends of said links, said plates overlapping the outer ends of said pins and each pin having a shoulder which bears against the outer side of the adjacent carrying arm.

ALBERT F. KRAUSE.
